SHARPENER FOR SHEARS

Merrill H. Johnson and Winfield H. Johnson
Moravia, Iowa

Application July 18, 1946; Serial No. 684,486

2 Claims. (Cl. 51—69)

1.

This invention relates to a sharpener for shears and it is primarily an object of the invention to provide a device of this kind wherein, during a working operation, is eliminated all vibration, end play and back lash.

Furthermore, it is a particular object of the invention to provide an apparatus of this kind which can be operated with equal facility to sharpen a plain or corrugated edge and to be employed in connection with varying bevels and with shears of differing sizes.

A still further object of the invention is to provide a device of this kind provided with means for effectively holding shears in a manner to permit effective use of an oil stone or a corrugating file.

The invention consists in the details of construction and in the combination and arrangement of the several parts of our improved sharpener for shears whereby certain important advantages are attained, as will be hereinafter more fully set forth.

In order that our invention may be better understood, we will now proceed to describe the same with reference to the accompanying drawings, wherein:

Figure 1 is a view in side elevation of a sharpener constructed in accordance with an embodiment of the invention;

Figure 2 is a sectional view taken substantially on the line 2—2, looking in the direction of the arrows;

Figure 3 is a view in top plan of Figure 1;

Figure 4 is a sectional view substantially on the line 4—4, of Figure 3, looking in the direction of the arrows;

Figure 5 is a sectional view on line 5—5, of Figure 4, looking in the direction of the arrows;

Figure 6 is a sectional view taken substantially on the line 6—6, of Figure 1, in the direction of the arrows;

Figure 7 is a fragmentary view partly in elevation and partly in section, illustrating another embodiment of the invention;

Figure 8 is a sectional view on line 8—8, of Figure 7, in the direction of the arrows; and

Figure 9 is a fragmentary longitudinal sectional view taken at substantially the transverse center of Figure 8.

In the embodiment of the invention as disclosed in the accompanying drawings, 1 denotes an elongated and substantially rectangular base plate of desired dimensions and provided with the openings 2 whereby, if desired, the same may be effectively secured to the top surface of a shelf

or other support by screws or other suitable means. The forward end portion of the base plate 1 at a desired point inwardly of said forward end is provided with the transversely spaced depending lugs 3 which provide stops to butt an edge of the support to which the device is applied although this is not essential.

The rear portion of the base plate 1 at a side margin thereof is provided with an upstanding web 4 of material height and which is provided with an elongated slot 5 substantially at right angles to the top face of the base plate 1. Insertible through this slot 5 is a threaded shank 6, the inner portion of which carries a fixed head or enlargement 7 for contact with the inner face of the web 4 and threading upon the outer end portion of the shank 6 is a holding or clamping nut 8 herein disclosed as of a winged type.

The extremity of the shank 6 inwardly of the web 4 is provided with a substantially spherical head 9 which is readily insertible through an opening 10 provided in an end portion of a sleeve 11. Engaging the inserted head 9 is the concave face of an outwardly spring-pressed jaw 12 within the inner portion of the sleeve and coacting with the outer side of the applied head 9 is a convex jaw face at the inner end of the plug 14 threading within the outer end of the sleeve 11. By this means the sleeve 11 is free for up and down swinging movement upon the head 9 and also has universal movement with respect thereto within certain limitations.

The closure for the closed end of the sleeve 11 herein comprises an inserted end portion of an elongated rod 15 which has free telescopic engagement within an elongated tubular member 16 or 17 which, in the present embodiment of the invention, are adapted to be independently used. The member 16 has operatively engaged with one end portion thereof a conventional handle or hand grasp 18 while the member 17 is similarly provided with a handle or hand grasp 19.

The member 16 is adapted to be employed in connection with an elongated flat file F provided at one extremity with a conventional tang 20 which is adapted to be tightly received within a socket 21 provided in the inner end face of the handle or hand grasp 18. The file F is also preferably of such dimensions as to extend to substantially the outer end of the member 16 when in working position.

The member 17 has swiveled connection, as at 22, with its handle or hand grasp 19 and clamped, as at 23, or otherwise rigidly held to the member 17 and extending a major distance

therealong is an open faced holding receptacle R for an oil stone S or equivalent abrading element. The holding receptacle R has its outer face open and includes the marginal flanges 24. Threading through one of the end flanges 24 for holding engagement with an applied stone S or its equivalent is a binding screw 25.

The extremity of the base plate 1 remote from the upstanding web and extending transversely thereacross is an upstanding jaw plate 26, the upper portion of which is forwardly and outwardly curved, as at a, while the top edge b, which is substantially sharp, has a longitudinal arch or bow.

The central portion of the plate 26 is provided with an opening 27 through which is freely insertible a bolt shank 28 provided at one extremity with a head 29 for contact with the rear face of the plate 26 and also with the upwardly facing shoulder 30 carried by said rear face of the plate 26 to hold the shank against rotation, said head 29 having a flat edge face c for engagement with said shoulder 30.

The shank 28 is of material length and is freely disposed through a central opening 31 in a movable jaw plate 32 provided at its rear outer corners with depending lugs 33 contacting from above with the portion 34 of the base plate 1 disposed forwardly of the fixed jaw plate 26. This permits the sliding jaw plate 32 to have a slight rocking movement to assure the most effective contact with the blade or cutting shears under the action of the winged nut N threading upon the outer or free end portions of the shank 28.

The upper or top marginal portion of the plate 32 has its inner face provided with a recess 36 formed to readily receive the blade 37 of a pair of shears and in a position to have the cutting edge of such blade sufficiently projected beyond the upper ends or marginal edges of the plates 26 and 32 to allow the sharpening element carried by either the member 16 or 17 to have effective engagement therewith. By selectively adjusting the position of the shank 6 along the slot 5, the angle of bevel of the action on the cutting edge of the blade of a pair of shears may be predetermined.

It is also to be pointed out that the inner upper marginal edge portion d of the plate 32 is longitudinally curved complementary to the longitudinal curvature of the adjacent edge b of the plate 26.

In practice, the blade 37 is placed within the recess 36 of the plate 32, with the outer extremity or point of the blade preferably extending about an eighth of an inch beyond a side of the plate 32. The blade is effectively clamped in such position by requisite tightening of the winged nut N. It is to be stated that the recess 36 provides a blade support.

The shank 6 is adjusted along the slot 5 of the web 4 in accordance with the angle of bevel desired. The member 16 is then telescopically engaged with the rod 15 and swung down to bring the file F in contact with the cutting edge of the clamped blade of the shears. If a plain edge is desired, the filing is started from the point of the blade to the left, with a full stroke of the file. However, if a corrugated edge is desired, the file F is placed on the heel of the shears and file to the right.

When it is desired to use the oil stone S or other abrading element, the member 17 is telescopically engaged with the rod 15 and in operation the stone S is pushed across the cutting edge

of the blade of the shears with reasonable pressure, starting at the heel of the shears, and during the pushing action the stone S is allowed to slide toward the point of the shears. The pushing action should at all times be outward or away from the person while in contact with the blade of the shears. It is also essential that there should be plenty of oil upon the stone S and that such oil should not be heavy.

- 10 With the use of the device as herein embodied, the blades of shears may be sharpened with just a few quick strokes, with the assurance of a keen lasting edge, either plain or corrugated, and in a manner which will not injure the shears. The holding of the shears during a working operation is such as to eliminate all vibration, end play and back lash and the curved edges b and d assure effective fitting of various sizes of shears with the desired set.
- 15 20 The plates 26 and 32 constitute a vise for holding a shear and such plates are of such curvature to set the points of the shears so that they will not pull at the point. When the nut N, on the shank 28 is tightened down, the plates 26 and 32 will 25 pull the point of the shear blade around whereby it is assured the shears will cut better on the point and from the point to the heel.

From the foregoing description it is thought to be obvious that a sharpener for shears constructed in accordance with our invention is particularly well adapted for use by reason of the convenience and facility with which it may be assembled and operated.

We claim:

- 35 1. A device of the class described comprising a long base member, a flat upstanding web carried by said member at one longitudinal edge and in a plane parallel with said edge, said web having a vertical slot substantially at right angles to the base member, a shank disposed through the slot, means for selectively holding the shank intermediate the ends of the slot, an elongated member, a substantially universal connection between the elongated member and the inner end of the shank whereby said long elongated member extends across the inner face of the web, a second elongated member carried by and slidable along the first member, an abrading element carried by the second elongated member, and means for supporting the blade upon the base member on a line perpendicular to the plane of the web for engagement by the abrading element carried by the second elongated member.

2. A device for sharpening a cutting blade, comprising a relatively long base plate, a fixed jaw member rigid with the base plate and standing vertically thereon adjacent to one end thereof, the jaw plate having a tapered top edge forming a clamping edge, a movable jaw plate mounted upon the base plate for rocking movement relative to the fixed jaw plate and having a top edge for coaction with the tapered edge of the fixed jaw plate, means carried upon the jaw face of the movable jaw plate forming a support for a cutting blade, said support being disposed at an inclination to the horizontal across the face of the movable jaw plate, an upstanding web extending lengthwise of one side of and carried by the base plate adjacent to the rear thereof, a ball carrying shank mounted in said upstanding web for vertical adjustment and extending inwardly in substantially parallel relation to the jaw plates, the ball of the shank being disposed above the base plate, a socket member receiving the ball of the shank, a rod carried by the socket member,

a tubular member slidably receiving the rod and carrying a handle at its outer end, and an abrading element secured longitudinally of and to the tubular member to extend across the opposing edges of the jaw plates.
